GARMENT

Howard E. Goldstein, Minneapolis, Minn.

Application March 26, 1949, Serial No. 83,593

2 Claims. (Cl. 2—80)

1

This invention relates to improved outer garments particularly adapted for children to afford protection in cold weather or while playing in the snow.

It is an object of my present invention to provide a combination garment embodying at least a bib or front-covering portion and a trousers portion, so constructed that the garment may be very quickly and easily put on or taken off.

More specifically, it is an object to provide an outdoor protection garment embodying a front section which extends from the neck or a position at the top of the chest, downwardly to the lower portions of the trouser legs and wherein this section may be released at its outer longitudinal edges throughout the entire length thereof so that the garment may be put on like a coat, brought about the ankles and closed at its front by slide fasteners or other conventional fastening means.

A further object is the provision of a garment of the class described wherein the central portion of the entire front comprises an inverted, generally V-shaped section connectible with longitudinal side edges of the balance of the garment, at the sides of the front, by slide fasteners or other fasteners and having simple but efficient underlying tabs with attachment elements for positively closing the top of the front of the garment to protect the wearer and prevent accidental opening of the fasteners and to hold the section in place while securing the fasteners.

This invention is an improvement in certain respects, upon the structure disclosed in Wallace Patent No. 1,973,421, granted September 11, 1934, and assigned to my company. It offers a more economical structure, serving most of the purposes of the Wallace structure without requiring overlapping of flap portions or reinforcing chest protection structure.

The foregoing and other objects will be apparent from the following description made in connection with the accompanying drawings wherein like reference characters refer to similar parts throughout the several views and in which:

Fig. 1 is a front elevation of a snow suit embodying my invention, showing the garment closed as it is worn in use;

Fig. 2 is a view similar to Fig. 1 showing in full lines one of the slide fasteners partially opened with the neck-closing elements unsnapped at one of the longitudinal edges of the front section and with the adjacent inner, upper longitudinal edge of the garment folded back to show the snap fastener element attached to the inner side there-

2

of, the dotted lines indicating the position of the front section when partially opened;

Fig. 3 is a fragmentary plan view taken from the rear or inside of the upper portion of the front section cut away; and

Fig. 4 is a front elevation of a combination suspender trousers and big top garment, embodying my invention, showing the front section closed with some portions broken away.

Referring now to the form of the invention shown in Figs. 1 to 3, I provide a snow suit embodying a combined coat and trousers having the back, sleeves and collar 6 of conventional construction. The front of the garment comprises 10 longitudinally disposed, relatively narrow side portions 7 which extend from the neck line or top of the garment downwardly in diverging spaced relation and which may be longitudinally connected at their side edges with the rear of the garment and which as shown, merge into the rear trouser sections of the garment. The upper ends of side portions or sections 7 may be stitched to the upper ends of the back portions across the shoulder line and leave a sleeve opening at each 20 side of the garment for securing the conventional sleeve 8 thereto. The collar 6 is attached by stitching circumferentially to the back and side sections 7, at the upper edges thereof.

The central front portion of the garment comprises an inverted V-shaped section 9, complementary shaped to the opening formed between the longitudinal edges of the front side sections 7 and extending from the front top of the garment or neckline, the full length of the garment and being bifurcated at the lower portion thereof, to form front trouser sections 9a. Trouser sections 9a, at their inner longitudinal edges, are stitched to the inner longitudinal edges of the back section of the trousers.

It will of course, be understood that the large, releasable front section 9 may be integrally formed or may as shown, constitute an upper triangular section for covering the central abdominal and chest portion of the wearer and a pair of generally oblong sections 9a, stitched to the upper triangular section at approximately the waist line or thereabouts and also, stitched together along a vertical line 9b at the central front portion of the garment. The releasable, over-all front section 9, as shown, extends at its longitudinal edges to the lower ends of the trouser portions proper and conventional slide fasteners at each side of the front section 9 releasably secure the longitudinal edges of the front section 45 to the inner longitudinal edges of the spaced

front side sections 7 of the garment. Said slide fasteners 10 embody the conventional cooperating series of interconnecting and overlapping lug elements 10a and the usual sliding cam element 10b for bringing the cooperating elements of each fastener into and out of locking engagement. The cam elements 10b slide upwardly from the bottom of the leg structures to the neck to close the front of the garment.

As shown, the lower edge of the trouser portions is closed in each instance and is provided with an elastic knit cuff 11.

At the upper end of the front section 9, I provide simple, economical and positive structure for closing and securing the upper front or neck portion of the garment. This structure as shown, comprises laterally extending fabric tabs 12 secured to the upper end of front section 9 and preferably to the rear side thereof and extending substantially circumferentially of the neck or upper chest of the wearer, to underlie the upper portions of the adjacent side-front sections 7 and to lie smoothly thereunder. The two tabs 12 may be integrally formed from a strip of material stitched in T formation to the upper end of the front section 9, as shown in Fig. 3. Each of the tabs 12 is provided on its outer face with a suitable, positive type attachment element such as a snap stud 13 while a cooperating fastening element such as a snap socket 14 is secured to the inner side of the adjacent upper portion of one of the side sections 7 adapted to cooperate with the element 13 when the front is closed near the top of the garment. Thus, the fastening elements of the two tabs 12 in cooperation with fastening elements on the inner sides of the top portions of side sections 7, positively close the garment at the upper front and secure the same to prevent accidental opening of the slide fasteners and to hold the bib or upper portion of the garment in place for securing the fasteners or if the fasteners are open.

In use, with the fastening elements 13 and 14, uncoupled, the entire central section of the garment may be opened, along lines diverging from the top of the garment to the lower ends of the trouser legs, leaving the enlarged, bifurcated front section 9 then connected to the back and sides of the garment only, the crotch portion of the trousers and the annular lower edges of the trousers. The wearer can then very easily get into the garment, slipping the feet through the cuffs of the trousers and putting on the garment in the manner of a coat, whereafter the central front section 9 may be raised and the slide fasteners moved upwardly to close the longitudinal edges at the front of the garment. Thereafter, or if desired, before action of the slide fastener, the neck and upper end of the garment may be closed and positively secured by coupling the cooperating fastener elements 13 and 14 at the front of the neck or over the upper portion of the chest.

In Fig. 2, the dotted lines indicate the upper portion of the front section 9 dropped down and constituting a large depending flap which naturally happens after disconnection of the tabs with the side portions 7 and after sliding the cam elements 10b of the slide fasteners downwardly to approximately the waist line. It is of course understood that the slide camming members 10b will slide to the extreme lower ends of the trousers to completely open up the front of the garment, including the front portions 8a of the trousers.

In Fig. 4, a high trousers-bib garment of the suspender type is illustrated, similar in structure to the front and trouser portions of the snow suit previously described. The trouser portion is cut high to extend at the rear, considerably above the waist line of the wearer. At the front of the garment, a generally triangular bib section 9b is integrally formed or otherwise secured by stitching to the top of the front trouser sections 9a which are of substantially identical structure to the corresponding trouser sections of the form first described. The narrow side sections of this bib garment, indicated by the numeral 15, may be integrally formed with the back section of the garment and extend in spaced relation at the front of the garment, longitudinally in upwardly converging spaced relation at the front of the garment similar to side sections 7 of the snow suit first described. Slide fastener elements 10 are provided between the mating edges of the releasable front section 9 and adjoining side sections 15 throughout substantially the full length of the garment, extending to the lower annular ends of the trousers proper and such slide fastener elements include the conventional slide cams 10b which are slidable upwardly to the upper end of the garment near the top of the chest and neck to close the garment. The upper ends of the front side members 15 are provided with suspender straps 16, preferably having adjustable buckles 15a, which extend over the shoulders of the wearer and are crossed or connected at the center of the back and are interconnected and which have their rear depending ends secured to the upper edge of the trouser portions, in conventional manner.

The upper end of the central front section 9 is provided with a pair of laterally extending, underlying tabs 12 provided with positive fastening elements 13 for underlying the adjacent upper portion of the side sections 15 and adapted to couple with cooperating fastening elements 14, affixed to the inner surfaces of said side sections 15, all substantially identical in structure with the tabs and cooperating fastening elements of the form first described.

From the foregoing description, it will be seen that I have provided a simple, economical, protective garment construction which enables a garment to be very quickly and easily put on or taken off and which provides a means for securing and closing the top of the garment while preventing inadvertent releasing of the longitudinal closing element.

It will of course be understood that various changes may be made in the form, details, arrangement and proportions of the parts without departing from the scope of my invention.

What I claim is:

1. An outdoor garment embodying a combined trousers and chest-covering portion split along lines diverging longitudinally from the top front of the garment downwardly along the trousers legs, leaving longitudinal front garment sections defining a front opening extending substantially the full length of the garment, a mating or complementarily shaped inverted V-shaped front section for closing the front opening, cooperating fastener elements along the edges of the inverted V-shaped section and said longitudinal sections for securing the corresponding edges of said sections together to form a closed front, the upper portion of said front section having a pair of laterally projecting portions secured thereto adapted to lap the longitudinal edges of said

longitudinal side sections, a fastening element on each of said lateral portions and a cooperating fastening element on each of said adjacent side sections for engaging the respective first mentioned fastening element whereby the top of the garment may be closed and held in place while securing the fasteners between said inverted V-shaped front and side sections.

2. An outdoor garment embodying a combined trousers and chest-covering portion split along lines diverging longitudinally from the top front of the garment downwardly along the trousers legs, leaving longitudinal front garment sections and defining a front opening extending substantially the full length of the garment, a mating or complementarily shaped inverted V-shaped front section for closing the front opening, cooperating fastener elements along the edges of the inverted V-shaped section and said longitudinal sections for securing the corresponding edges of said sections together to form a closed front, a pair of tabs secured to the top of the front sec-

tion and extending from each side thereof at an obtuse angle with respect to the side edges of the front section and adapted to lap the longitudinal edges of said longitudinal side sections, a fastening element on one end of each tab and a cooperating fastening element on each of said adjacent side sections immediately below the neck line thereof for engaging the respective first mentioned fastening elements of the tabs, whereby the tabs extend circumferentially of the neck line of the wearer and the garment and lie smoothly against the side sections.

HOWARD E. GOLDSTEIN.
